CALCULATING MACHINE

Thomas M. Butler, Detroit, Mich., assignor to Burroughs Adding Machine Company, Detroit, Mich., a corporation of Michigan

Original application October 12, 1935, Serial No. 44,751. Divided and this application May 22, 1937, Serial No. 144,283

5 Claims. (Cl. 235—137)

This invention relates to a tens-transfer mechanism. The application is a division of my co-pending application Serial No. 44,751, filed October 12, 1935.

5 The main object of the invention is to provide an improved tens-transfer mechanism.

Other and more particular objects will appear from the following specification and drawings.

An embodiment of the invention is shown in 10 the accompanying drawings in which:

Figure 1 is a right side elevation of a machine in which the tens-transfer mechanism may be used.

15 Fig. 2 is a partial side elevation and section of said machine showing some of the controls for the tens-transfer mechanism.

Fig. 3 is a partial side elevation and section of the tens-transfer mechanism showing the same with the parts in the position they occupy after 20 an initial transfer has taken place.

Fig. 4 is a detailed right side elevation and section of the tens-transfer mechanism, a mechanism being shown for each of two registers, of the machine illustrated, the parts being in positions they occupy after a full transfer has occurred.

The invention is shown as applied to the machine disclosed in my co-pending application heretofore referred to but it will be understood 30 that it may be applied to other types of machines as well.

General machine construction

The machine is provided with a plurality of 35 banks of depressible amount keys 1 that are used for indexing an item in the machine. When said keys are depressed, their stems are adapted to arrest index bars 2 that are connected to actuator racks 3.

40 The machine is given a cycle of operation by first rocking a main drive shaft 4 counterclockwise from the position of Fig. 1 and then returning it clockwise. These two movements are often called the forward and the return stroke of the

45 machine. The drive shaft may be oscillated by means of a hand crank or by a motor, a portion of the motor being shown at 5 in Fig. 1. When a hand crank is used, it is connected directly to the shaft 4.

50 During the forward stroke of the machine, the index bars 2 move forward to differential positions determined by the depressed amount keys and this differentially positions the actuator racks. The racks differentially position type bars 55 6 (Fig. 1), and the hammers 7 of a printing mech-

anism are then operated near the end of the forward stroke to print the item that has been indexed.

The paper on which the type impressions are made is carried by a platen P supported on a 5 carrier 8 which, in the machine shown, is stationary.

The machine shown has a main registering mechanism and a plurality of subordinate or multiple registering mechanisms. The tens-transfer mechanism is shown in connection with each but will be described in connection with the main register.

Addition is performed by rocking the register into engagement with the actuator racks after 15 they have been differentially positioned. The actuators are then returned to normal during the return stroke of the machine which causes the item indexed by the keys to be entered in the register.

20 The machine is normally conditioned for addition but it may be conditioned for subtraction by means of a subtract lever or, as in this case, by means of a subtract key "Subt." Subtraction is performed by rocking the register into engagement with the actuators before they are moved to differential position and by then rocking the register out of engagement with said actuators after they have been moved to differential position. This results in rotating the register pinions in the opposite direction to which they are 25 rotated for addition.

A bank of control keys is provided along the right-hand side of the keyboard to control the 35 conditioning of the machine for various functions such as totaling, sub-totaling, etc. Totals and sub-totals may be taken, the machine may be non-added, errors may be corrected, and various other controls provided, but these mechanisms will not be described in detail in this case 40 as they are not necessary for an understanding of the tens-transfer mechanism.

Main registering mechanism

The registering mechanism comprises a plurality of register pinions 10 rotatably mounted on a shaft carried by a rockable register frame 11. The register frame is urged toward a position where the register pinions are out of engagement with the actuators by a spring (not 45 shown) but it may be rocked into engagement with them by means of a cam 14 pivoted at 14a (Fig. 4), which cam is rocked by power derived from the main drive shaft of the machine through connections described in detail in the parent ap- 50 55

lication and not of particular importance here. It is sufficient to understand that, at the beginning of the return stroke of the machine, the cam 14 is rocked counterclockwise (Fig. 4) to move the register into engagement with the actuators. This movement occurs immediately at the beginning of the return stroke so that the register is rocked into engagement with the actuators before they start their return movement. After the actuators have been returned to normal, and near the end of the machine cycle, the register is moved out of engagement with the actuators.

More specifically, and referring to Fig. 4, the cam 14 which controls the main register is rocked by means of a crank arm 20 fixed to the same shaft as said cam, said crank arm being urged counterclockwise as viewed in Fig. 4 by a spring 28a. Connected to the crank arm 20 are two links 21 and 22. The link 22 is connected to one arm of a bell crank yoke 23 pivoted on a stationary stud 28a. The other arm of the bell crank yoke 23 carries a pivoted pawl 24 having a hooked nose. This pawl also has a notch 25 near its nose 26 and a tail piece 26. The pawl is urged counterclockwise as viewed in Fig. 4 by a spring 27. The link 21 is connected to one arm of a bell crank lever 28 pivoted at 28a. The other arm of this bell crank has a long pawl 29 pivoted to it at 28a. This pawl 29 is in the form of a yoke urged clockwise by a spring 30 and it has a long nose on its lower end with a notch 31 near said nose.

The pawls 24 and 29 are adapted to engage the stud 18, which is rocked during each machine cycle, for the purpose of rocking the main register into and out of engagement with the actuators as will presently appear.

The main register controls are normally in addition condition as shown in Fig. 4. As the stud 18 moves upward it moves along the edge of pawl 24 and, near the end of the upward movement of said stud, the pawl is rocked counterclockwise by its spring to cause the notch 25 to engage over the stud 18. During the return movement of stud 18 the pawl 24 is moved downwardly which rocks the bell crank yoke 23 counterclockwise and pulls the link 22 forward to rock the register controlling cam 14 counterclockwise to move the register into engagement with the actuators. This movement of the register occurs immediately at the beginning of the return stroke of the machine so that the register is rocked into engagement with the actuators before they start on their return movement.

After the actuators have been returned to normal, and near the end of the cycle of machine operation, the register is moved out of engagement with the actuators. When the bell crank yoke 23 was rocked counterclockwise as above explained and the link 22 pulled forward, the link 21 was also pulled forward. The latter rocked the bell crank 28 clockwise about its pivot 28a which pulled the pawl 29 upward. The parts are proportioned so that near the end of the downward movement of stud 18 said stud engages the long nose of pawl 29 and pulls the pawl downward to rock bell crank 28 counterclockwise to thrust neck 21 rearward to rock cam 14 to release the register so that it will be pulled out of engagement with the actuators by its spring. Also, during the downward movement of stud 18, the tail 26 of pawl 24 engages a stud 32 which causes pawl 24 to be rocked clockwise so as to release itself from stud 18 to thereby permit the stud to move pawl 29.

The main register is thus rocked into engage-

ment with the actuators after they have been differentially positioned, continues in engagement with them during their return movement, and is moved out of engagement with them after the item has been entered on the register.

Subtraction in main register

An item may be subtracted from the main register by entering the item on the amount keys, depressing the subtract key, and depressing the 10 main register motor bar, "Main reg." (Fig. 1).

Depression of the subtract key conditions the controls for the main register so that the register will be rocked into engagement with the actuators prior to their movement, and moved out of engagement after said actuators have been differentially positioned. This results in rotating the register pinions in the opposite direction to their rotation for addition.

The stem of the subtract key 40 (Fig. 2) is positioned over one arm 41 of a bell crank lever pivoted on a shaft 42 and urged clockwise by a spring 43. This bell crank lever has another arm 44 carrying a stud 45 positioned to the rear of a U-shaped member 46 pivoted on the end of a lever 47 that is journaled on shaft 48. The U-shaped member 46 is urged clockwise by a spring 49 and it has a shoulder 50 that is adapted to be positioned under a lateral lug on a projection 51 of the stem 34 of the main register motor bar. The lever 47 has an upwardly extending arm 52 carrying a stud 53 engaging the edge of an extension 54 of the subtract pawl 29. When the subtract key is depressed, the bell crank 41-44 is rocked counterclockwise, which moves stud 45 rearwardly and allows U-shaped member 46 to swing clockwise to a position where its shoulder is under the lug on motor-bar-extension 51. If the main register motor bar is then depressed, the lever 47 will be rocked counterclockwise, which moves stud 53 away from extension 54 and allows pawl 29 to move to a position to cause notch 31 to engage stud 18 which is moved upwardly and then returned downwardly during each machine cycle.

Accordingly, at the beginning of a subtraction cycle of machine operation, the bell crank 28 to which pawl 29 is connected is rocked clockwise about its pivot 28a to pull link 21 forward to rock the register control cam 14 (Fig. 4) counterclockwise about its pivot 14a to cause the register to engage the actuators. As the stud 18 moves upwardly the pawl 29 is disengaged from it by reason of the fact that a projection on an extension 54a of said pawl (Fig. 4) engages a stationary lug 55 on the machine to cause the pawl to be cammed counterclockwise. Near the end of the forward stroke of the machine, that is, when the stud 18 approaches its upper limit, the stud 18 engages the nose 25 of the pawl 24 (Fig. 4), pivoted on bell crank 28, and rocks said bell crank 60 clockwise to rock the register cam 14 clockwise to permit the register to move out of engagement with the actuators.

In order to prevent the pawl 24 from being positioned with its notch 25 over stud 18 so that it will act to rock the register back into engagement with the actuators at the beginning of the next cycle, a lever 56 is provided, which will be called the "non-add" lever. This lever is positioned so that it will engage a stud 57 on pawl 24 (Fig. 2). The lever 56 is one arm of a bell crank yoke pivoted on a shaft 58 and it has a forwardly extending arm 59 on it which terminates in an abutment end adapted to be engaged by the end of arm 44 of bell crank 41-44. When the subtract key is depressed, the end of arm 44 engages

the end of arm 59 and rocks arm 56 clockwise to cause it to engage stud 57 to move pawl 24 to a position such that, while its nose is still in the path of stud 18, the stud 18 will not engage in 5 the notch in pawl 24.

The main register is thus rocked into engagement with the actuators prior to their movement and rocked out of engagement with them after they have been differentially positioned.

10 The cycle of machine operation for subtraction is caused by depressing the main register motor bar 33. This selects the main register for operation and disables the controls for the multiple registers, as described in the parent application, 15 so that the item will not be subtracted from the multiple registers.

Tens-transfer mechanism

20 The tens-transfer mechanism will effect both "carries" and "borrows." It includes a plurality of transfer segments 60 (Fig. 3), of which there is one for each register pinion. The segments are pivoted on a shaft 61 and are adapted to be engaged by the register pinions when the latter are rocked out of engagement with the actuators, the engaged position being shown in Fig. 3, and the disengaged position in Fig. 4.

25 Each of the register pinions 10 has a wide tooth 62 (Fig. 3) adapted to engage the nose 63 of a pawl 64 when the register pinion moves from its 9 to 0 or through its 0 position and vice versa. The pawl 64 is pivoted on a shaft 65 carried by the rockable register frame 11. The lower end of 30 the pawl has a lateral lug 66 normally positioned behind one arm of a bell crank latch lever 67 pivoted on a stationary shaft 68. The latch 67 is urged counterclockwise as viewed in Fig. 3 by a spring 69. The other arm of the bell crank 35 latch 67 has a shoulder 70 normally positioned behind a lug 71 on an arm 72 pivoted on a shaft 73 and urged clockwise as viewed in Fig. 3 by a spring 74. The latched position of the parts is shown in Fig. 2. The upper end of arm 72 carries a stud 75 operating in a slot 76 in one of the 40 transfer segments 60. It is to be understood that a plurality of pawls, arms, and latches are provided and that a given pawl 67 and arm 72 are controlled by a given register pinion and that such arm 72 controls the transfer segment 60 for 45 the register pinion of next higher order.

50 Assume that the register pinions 10 are in engagement with the actuators (Fig. 3) and that the tens-transfer mechanism is in condition to "borrow", that is, effect a tens-transfer in subtraction operations. This is the condition of the mechanism as illustrated in Figs. 3 and 4. If a given register pinion moves from its 0 to 0 or through its 9 position, the wide-faced tooth 62 55 engages the nose of pawl 64 and rocks the pawl clockwise. This rocks the bell crank latch 67 latchwise and releases the arm 72 which is thereupon moved clockwise by its spring 74. The movement of arm 72 is limited by reason of the 60 fact that it is a part of a yoke having another arm 77 that limits against a cross bar 78 as shown in Fig. 3. The arm 72 moves from the dot-dash position of Fig. 3 to the full-line position and causes what is called an "initial" or "partial transfer." The parts remain in this position until the register is rocked out of engagement with the actuators.

65 It will be recalled that the register is rocked out of engagement with the actuators under the control of a cam 14 shown in dotted lines in Fig. 3. This cam is rocked clockwise from its Fig. 3

position to release the register. Connected to this cam is a link 80 whose lower end is connected to a pivoted arm 81. This arm has an abutment end 82 adapted to engage a roller 83 on a crank arm 84 fixed to a shaft 85 that carries the cross bar or bail 78. Arm 84 and shaft 85 are urged counterclockwise by a spring 86. Near the end of a cycle of machine operation, and after the register 10 has been rocked out of engagement with the actuators and into engagement with the transfer segments, the abutment 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 On the other hand, if the directing member 90 is in the position shown in the lower part of Fig. 4, the stud 78 on arm 72 will, when said arm is rocked clockwise, rock the segment 60 clockwise. The segment 60 has a lower lug 94 that is engaged by the edge of the arm 92 so that the segment 60 moves clockwise with arm 92. It thus becomes evident that, by changing the position of member 90, the direction of movement of the transfer segment may be changed. This change occurs without putting a tension of any kind on the transfer segment. The result is that, when the tens-transfer mechanism is changed from one condition to the other, there is no tendency for the transfer segments to be moved to cause the register pinions to be thrown out of alignment.

Further, when the lever 72 is changed from the dot-dash to the full-line position of Fig. 3 by an "initial carry," or transfer, the stud 78 moves in a portion of slot 76 that is concentric with the axis of lever 72 so that the transfer segment is not moved, even slightly.

The tens-transfer mechanism is normally in add condition but it is changed automatically from "carry" to "borrow" as an incident to the change of the machine from addition to subtraction condition, and vice versa. The rear end of arm 92 (Fig. 3) has a notch 98 in which is positioned a ball 95. The ball 95 is urged downwardly by gravity which is preferably assisted by a spring 99 (Fig. 4). Said ball is carried by arms that form an integral part of a yoke 97 pivoted on the shaft 61. The left-hand arm of this yoke viewed from the front of the machine is numbered 96 and the right-hand arm is numbered 106 in Fig. 2.

Referring to Fig. 2, it will be recalled that the subtract key stem is positioned over one arm 41 of the bell crank lever 41-44 which, when the subtract key is depressed, frees the U-shaped member 46 that is pivoted on the end of lever 47. The rear end of lever 47 is connected by a spring 100 to one arm 101 of a ball 102 pivoted at 103. The other arm 104 of this ball is positioned to engage a stud 105 on an arm 106 which is integral with the yoke 97 that controls the add-subtract condition of the tens-transfer mechanism.

When the main motor bar is depressed, after the subtract key has been depressed, the U-shaped member 46 is moved downward, which rocks lever 47 counterclockwise. The latter rocks ball 102 clockwise and the yoke 97 is, in turn, rocked counterclockwise. Counterclockwise movement of yoke 97 moves ball 95 counterclockwise which in turn moves member 90 counterclockwise, and this changes the tens-transfer mechanism from carry to borrow condition.

From this it will be clear that depression of the subtract key conditions the mechanism, i. e., controls the position of the U-shaped member 46, and that depression of the main motor bar moves the parts to change the tens-transfer mechanism from add to subtract condition.

The tripped transfer segments are restored upon the next movement of the register into engagement with the actuators. The cam 14 must be rocked counterclockwise from its Fig. 4 position to effect such movement. When the cam rocks counterclockwise, it pulls link 80 upward which rocks arm 81 counterclockwise. Arm 81 carries a restoring ball 117 (Fig. 4) which engages the tails 77 of arms 72 and restores said arms to normal latched position. Restoration of

arms 72 also restores the transfer segments to normal.

At the end of a subtract operation, and after the motor bar and subtract key are returned to normal, the parts moved by the motor bar are restored to normal, which releases the yoke 97 that is thereupon restored to normal by its spring.

I claim:

1. In a tens-transfer mechanism for calculating machine registers having a plurality of register pinions, a transfer segment for moving a register pinion, said segment having a substantially pear-shaped slot in it, an actuating member controlled by the register pinion of next lower order, said actuating member having a stud adapted to operate in said pear-shaped slot, a directing member adjacent said slot for determining the direction of action of said stud in moving said transfer segment, said directing member being freely movable to different positions relative to said slot without tending to move said transfer segment but being connected to said segment so that, when said actuating member is moved, said stud will move said directing member to move said transfer segment in one direction or the other, and means for changing the position of said directing member in accordance with the addition or subtraction condition of the machine.

2. In a calculating machine having actuators, a register, and means for conditioning said machine for addition or subtraction in said register; a tens-transfer mechanism of the type in which, when the register pinions are disconnected from the actuators, they are connected to tens-transfer segments; said tens-transfer mechanism comprising, as to each two adjacent orders, a tens-transfer segment for one order, a pivoted actuating member for said transfer segment, means controlled by the register pinion of next lower order for causing said actuating member to be rocked to an "initial transfer" position, said actuating member having a stud on its operating in a slot in said transfer segment, the edges of said slot fitting closely against said stud and being curved on arcs whose center of curvature is the axis about which said actuating member rocks whereby said actuating member may move to "initial transfer" position without moving said transfer segment and while holding said segment against movement, a directing member adjacent said slot for determining the direction of action of said stud in moving said transfer segment when said actuating member is moved to complete the tens-transfer, said directing member being freely movable to different positions relative to said slot without tending to move said transfer segment but being connected to said segment so that, when said actuating member is moved, said stud will move said directing member to move said segment, and means for changing the position of said directing member in accordance with the addition or subtraction condition of the machine.

3. In a calculating machine having actuators, a register, and means for conditioning the machine for addition or subtraction in said register; a tens-transfer mechanism of the type in which, when the register pinions are disconnected from the actuators, they are connected with tens-transfer segments; said tens-transfer mechanism comprising, as between two orders, a toothed transfer segment with which a register pinion may engage, a single movable actuating member for moving said transfer segment, means for

moving said member, means governed by the register pinion of next lower order for controlling said member, a driving connection between said actuating member and said transfer segment, 5 including a camming member shiftable relative to said segment but operably connected to the segment to move it, said actuating member and its driving connection acting positively on said segment and constituting the sole means acting 10 on said transfer segment to move it, and means conditioned automatically by the change of said machine from addition to subtraction condition and vice versa for shifting said camming member whereby, when said actuating member is moved, said transfer segment will be moved in one direction or the other to thereby effect "carries" or "borrows" in accordance with the addition or subtraction condition of the machine.

4. In a calculating machine having actuators, 20 a register, and means for conditioning the machine for addition or subtraction in said register; a tens-transfer mechanism of the type in which, when the register pinions are disconnected from the actuators, they are connected to tens-transfer 25 segments; said tens-transfer mechanism comprising, as between any two orders, a toothed transfer segment with which a register pinion may engage, a single movable actuating member for moving said transfer segment controlled by 30 the register pinion of next lower order, means for moving said member, a pin-and-slot driving connection between said actuating member and said transfer segment, said driving connection including a slot in said transfer segment and a movable directing member operably connected to said 35 segment to move it and positioned adjacent said slot for determining the direction of action of said driving connection on said transfer segment, and means governed by the change of said machine from addition to subtraction condition and

vice versa for automatically positioning said directing member whereby, when said actuating member is moved, said transfer segment will be moved in one direction or the other to effect "carries" or "borrows" in accordance with the addition or subtraction condition of the machine. 5

5. In a calculating machine having actuators, a register, and means for conditioning said machine for addition or subtraction in said register; a tens-transfer mechanism of the type in which, 10 when the register pinions are disconnected from the actuators, they are connected to tens-transfer segments, said tens-transfer mechanism comprising, as to each two adjacent orders, a tens-transfer segment for one order, a movable actuating member for moving said transfer segment, means controlled by the register pinion of next lower order for causing said actuating member to move to an "initial transfer" position, a driving connection between said actuating member and said transfer segment, including a camming member shiftable relative to said segment but operably connected to the segment to move it, said connection being constructed and arranged to enable 20 said member to move to "initial transfer" position without causing any movement of said segment and while holding said segment against movement, means for causing said actuating member to move to complete the tens-transfer, 25 said actuating member and its driving connection acting positively on said segment and being the sole means acting on said segment to move it, and means for shifting said camming member to change the direction of movement of said tens-transfer segment during said completing movement of said actuating member in accordance 30 with the addition or subtraction condition of the machine. 35
